Attnys.

UNITED STATES PATENT OFFICE.

HERBERT H. MOORE, OF CHICAGO, ILLINOIS, ASSIGNOR TO SWIFT AND COMPANY, A CORPORATION OF ILLINOIS.

BRANDING-TOOL.

1,164,742.

Specification of Letters Patent. Patented Dec. 21, 1915.

Application filed June 10, 1915. Serial No. 33,280.

To all whom it may concern:

Be it known that I, HERBERT H. MOORE, a citizen of the United States of America, and a resident of Chicago, county of Cook, and 5 State of Illinois, have invented certain new and useful Improvements in Branding-Tools, of which the following is a specification.

The main objects of this invention are to provide an improved form of branding tool 10 constructed so that the branding characters are capable of adjusting themselves to the irregularities in the surface of the object to be branded; to provide an improved mounting of the characters whereby they are 15 movable relative to the supporting member individually or in groups, so that all of the characters may be simultaneously impressed upon the object with substantially equal pressure; and to provide an improved tool 20 of this kind which is capable of making the brand by means of ink or by the application of heat.

An illustrative embodiment of this invention is shown in the accompanying drawings, in which,

Figure 1 is a perspective view of the improved branding tool. Fig. 2 is a bottom plan of the same showing the character of the brand embodied in the tool herein described.

In the construction herein shown, the tool comprises a support or frame 1 on which character-supporting members 2 are mounted. This frame is formed of a pair of bars 35 or plates 7 and 8 spaced apart by spacing blocks 9 and secured together with said spacing blocks by means of bolts and nuts 10. A handle 3 is attached to said frame by means of which the tool is operated. The 40 members 2 are separately carried on stems 4 slidably mounted on the frame 1 so that the members are independently movable transversely to said frame, whereby when the characters are impressed upon the object to be branded, the members may yield 45 so as to accommodate themselves to the irregularities in the surface of said object. The characters or letters of the brand are formed on the under side of the members 2, as is more clearly shown in Fig. 2, being 50 preferably embossed or raised forms. The characters may be arranged one on each member, or two or more letters may be placed on one member as may be desired or

as conditions may require. The stems 4 are 55 preferably of rectangular cross-section and are slidably supported in rectangular apertures in the frame 1, whereby the members 2 are held against turning. Springs 5 on the rods 4 between the members 2 and the 60 frame 1, are arranged so as to yieldingly resist movement of said members transversely to the frame, when the tool is being pressed onto the object. These springs are quite stiff so that sufficient pressure may be individually applied to the members to effect the imprint of all of the characters of the brand. In the form herein shown, the 65 springs normally urge the members 2 so that the characters are brought into alignment. Pins or shoulders 6 secured to the stems 4 between the plates 7 and 8 limit the 70 movement of the stems.

The tool is intended for all branding purposes and may be constructed so as to make 75 the brand either with the use of ink or the application of heat.

Although but one specific embodiment of this invention has been herein shown and described, it will be understood that numerous details of the construction shown may be altered or omitted without departing from the spirit of this invention as defined by the following claims.

I claim:—

1. A branding tool, comprising a support 85 formed of a pair of spaced bars, a plurality of members, branding characters formed on said members, stems carrying said members and slidably mounted on said bars whereby 90 said members are independently shiftable transversely to said support, springs interposed between said members and the adjacent bar of said support and adapted to transmit pressure from said support individually to said members, and shoulders on said stems between said bars arranged to coact therewith to limit the transverse movement of said members.

2. A branding tool, comprising a support 100 formed of a pair of plates secured together in spaced relation, a plurality of members, branding characters formed on said members, non-rotatable stems carrying said members and slidably mounted on said 105 plates whereby said members are independently shiftable transversely to said support, springs embracing said stems between said

members and the adjacent plate of said support and adapted to transmit pressure from said support individually to said members, and shoulders on said stems between said 5 plates arranged to coact therewith for limiting the transverse movement of said members.

Signed at Chicago this 7th day of June, 1915.

HERBERT H. MOORE.
